CLAIM

The ornamental design for a floor cleaning machine, as shown and described.

DESCRIPTION

FIG. 1 is a front perspective view of a floor cleaning machine showing my new design;

FIG. 2 is a front view thereof;

FIG. 3 is a right side view thereof;

FIG. 4 is a rear view thereof;

FIG. 5 is a left side view thereof;

FIG. 6 is rear perspective view thereof;

FIG. 7 is top view thereof; and,

FIG. 8 is a bottom view thereof.

The broken lines illustrating portions of the floor cleaning machine are for environmental purposes only and form no part of the claimed design.
